3,118,651 LIFTING JACK

Arthur C. Achterberg and Stephen H. Paul, St. Joseph, Mich., assignors to Auto Specialties Manufacturing Co., St. Joseph, Mich., a corporation of Michigan
Filed Apr. 13, 1962, Ser. No. 187,329
9 Claims. (Cl. 254—101)

The present invention relates to a novel lifting jack, and more specifically to a novel jack adapted to be used for engaging and lifting a bumper or other desired part of a vehicle.

An important object of the present invention is to provide a novel lifting jack having load lifting means which may be operated easily and without requiring great strength on the part of the operator and which may be safely operated without danger of injury to the operator both during raising and lowering of the load.

Another object of the present invention is to provide a novel lifting jack having actuating means constructed so that it is readily adjustable for enabling an operator to vary the mechanical advantage provided thereby.

Still another object of the present invention is to provide a novel lifting jack having parts formed for minimizing friction therebetween and for resisting corrosion for permitting ease of operation and extended working life.

A more specific object of the present invention is to provide a novel lifting jack of economical and compact construction and adapted to be readily assembled or disassembled to facilitate storage thereof.

Other objects and advantages of the present invention will become apparent from the following description and the accompanying drawing, wherein:

FIG. 1 is an elevational view partially in cross-section showing a lifting jack incorporating features of the present invention;

FIG. 2 is a fragmentary plan view of the novel lifting jack;

FIG. 3 is a fragmentary sectional view taken along line 3—3 in FIG. 4; and

FIG. 4 is a fragmentary sectional view taken along line 4—4 in FIG. 1.

Referring now more specifically to the drawings, wherein like parts are designated by the same numerals throughout the various figures, a lifting jack incorporating features of the present invention comprises an upstanding screw rod or column 10 detachably connected with and supported by a foot member 12. Load lifting means 14 is mounted on the screw rod for engaging an automobile bumper or any other desired object to be lifted.

The screw rod 10 is provided with helical thread convolutions 16 which extend from its upper end toward but short of its lower end so that the lower end has an unthreaded portion 18. An integral lug 20 is formed on a side of the unthreaded lower end portion 18 for cooperative engagement with the foot member 12 for preventing rotation of the screw rod about its own axis. After the load lifting means is assembled with the screw rod, a nib or stop element 22 is formed on the screw rod, as shown in FIG. 1, for limiting upward movement of the load lifting means along the rod. It is to be noted that the stop 22 is spaced substantially below the upper end of the rod. As a result, the uppermost position of a nut element of the load lifting means, to be described hereafter, is determined by the stop element 22 and is well below the upper end of the screw rod. The substantial portion of the rod above the stop element aids in strengthening and rigidifying the portion of the rod or column beneath and relatively adjacent to the stop 22.

The foot member 12 comprises a generally rectangular sheet metal base portion 24 adapted to rest on the ground or any other support surface. A section 26 of the base

2

portion is raised above the peripheral edge of the base portion and is provided with a central socket or well 28 adapted to receive and retain the lowermost end of the screw rod. An inverted cup-shaped element 30 is welded or otherwise secured to the raised section 26 of the base portion. An upper end wall 32 of the cup-shaped element is formed with a central aperture 34 therethrough substantially vertically aligned with the socket 28 and also adapted to receive and snugly confine the unthreaded lower end portion 18 of the screw rod. A notch 36 is cut in the margin of the aperture 34 for interengagement with the lug 20 on the screw rod.

The load lifting means includes an elongated nut member 38 threaded onto the screw rod 16 and preferably having a length substantially equal to or in excess of twice its internal diameter for promoting ease of operation. An inverted beveled crown gear element 40 is integrally formed with the nut member 38, which gear element is adapted to be driven in the manner described in detail below for rotating the nut member and thereby raising or lowering the load lifting means.

A thrust bearing washer 42 is assembled over the screw rod and on top of the nut member 38 and separates the nut member from an elongated tubular sleeve portion 44 of a carrier member 46. The washer has an inverted cup-like shape presenting a depending flange 43 surrounding and spaced from the upper end of the nut member for preventing dirt and the like from entering between the nut member and the washer. The tubular sleeve portion 44 closely but slidably receives the screw rod and has a length preferably in excess of twice its internal diameter for minimizing any tendency of the sleeve portion to twist and bind on the screw rod. Radiating grooves 48 are formed in and spaced around the upper end of the nut member 38, as shown in FIGS. 3 and 4, for reducing frictional engagement between the nut member and the thrust bearing washer 42, and also for providing troughs for accumulating and discharging any dust or other residue which may be formed between the engaging surfaces of the nut member and the thrust washer.

The carrier member 46 includes an arm 50 integrally formed with the sleeve portion 44 and extending rearwardly and downwardly from the sleeve portion in a diagonal direction as shown best in FIG. 1. The lower end of the arm 50 merges with an integral tubular bearing portion 52. The bearing portion 52 rotatably receives and supports an elongated shank section 54 of a pinion 56 which meshes with the gear element 40.

In order to operate the gear structure, a handle member 58 is provided. The handle member is in the form of an elongated rod or bar having a straight shank section 60 extending through a transverse aperture 62 formed in the shank or hub portion 54 of the pinion. An outer end portion 64 of the bar is bent so as to extend generally perpendicularly from the shank section 60. An upper end section 66 of the handle bar is flattened and transversely enlarged as shown in FIGS. 1 and 2, so that its major transverse dimension is substantially greater than the diameter of the aperture 62. The transversely enlarged end portion 66 serves to retain the handle member in assembled relationship with the pinion shank 54. Furthermore it is to be noted that the flattened and enlarged end section 66 is adapted to be engaged within a notch 68 formed in the pinion shank portion 54 by sliding the handle member downwardly from the position shown in FIG. 1. When the end portion 66 is engaged within the notch 68, the handle member 58 will be locked against rotation about the axis of its shank portion 60 for promoting easier manual manipulation or rotation of the handle member and thus actuation of the lifting jack.

As suggested in the preceding paragraph, the handle

member 53 may be adjusted by sliding the section 60 thereof through the aperture 62. Thus, the operator can adjust the mechanical advantage provided by the handle member in accordance with the requirements of a particular situation. Furthermore the handle member may be adjusted and rotated so that the end portion 64 turns inwardly for decreasing the amount of space required for storage purposes.

The carrier member 46 comprises an integral load supporting projection 70 extending forwardly from the sleeve portion 44. The portion 70 may be extended for directly engaging an automobile bumper or other article to be lifted. However, in the specific embodiment shown, the projection 70 is adapted to receive and support a load engageable saddle member 72. The member 72 is formed from sheet metal and is provided with spaced opposite side portions 74 and 76 which embrace the element 70, as shown in FIGS. 1 and 2, and which are connected by a bight portion 78. The bight portion 78 may be provided with the generally hooked configuration shown for accommodating the contour of a bumper or other article to be engaged. A pivot pin 80 extends between and is secured to the side sections 74 and 76 and is adapted to rest on the load lifting projection 70.

The projection 70 is formed with an upper surface 82 which extends upwardly and outwardly so that the pin 80 tends to be held by gravity in a seat 84 at the lower end of the surface 82. A spring retainer element 86 is anchored to the sleeve portion 44 and extends over and engages the pin 80 for releasably holding the pin against seat 84. An outer end portion 88 of the spring retainer which is formed from spring wire in the manner shown projects upwardly for facilitating insertion of the pin 80 beneath the spring retainer when the load engageable member 70 is assembled with the carrier member.

When the jack unit is in the generally upright position shown in FIG. 1, it will be observed that the upper surface 82 of the load lifting projection 70 is inclined upwardly sufficiently to retain the pivot pin 80. At the same time the upward inclination of the surface 82 is such that in the event that the vehicle being lifted rolls backwardly so as to fall from the jack, the pin 80 will slip forwardly from the surface 82 for releasing the load engaging member 72 and thereby prevent injury to either the jack unit or the vehicle. It may also be noted that when the jack is in the normal upright position the construction is such that the axis of the pinion 56 is inclined upwardly and rearwardly slightly from the horizontal. As a result, the handle member 53 normally is positioned for rotation in a plane inclined slightly forwardly with respect to the upstanding screw rod 16. In certain situations, the jack unit may tend to tilt rearwardly a slight amount when placed under the load of a vehicle, whereby the handle member is shifted to a more vertical position. The arrangement is such that when the handle member extends downwardly, as shown in FIG. 1, the lower end thereof will always be positioned slightly behind the pinion during normal operation of the unit for facilitating access thereto by the operator and promoting easier operation of the unit.

The screw rod or column 16 is preferably of a rolled construction which provides a smooth finish. The rolling operation also causes work hardening of the screw rod which enhances the rigidity of the column. In order further to provide a smooth surface for reducing friction, the screw rod is subjected to a phosphate treatment for increasing corrosion resistance and also to an application of a suitable dry lubricant.

The nut and gear member, the pinion, and the carrier 46 are preferably made from a zinc base die cast alloy. Such a material provides self lubricating characteristics and good resistance to corrosion for further promoting ease of operation and a long working life.

While the preferred embodiment of the present invention has been shown and described herein, it is obvious

that many structural details may be changed without departing from the spirit and scope of the appended claims.

The invention is claimed as follows:

1. A lifting jack comprising an upstanding screw rod, a foot member receiving and retaining a lower end of the rod and supporting said rod in an upstanding position, a nut member threadedly mounted on said rod and movable along the rod upon rotation of the nut member, said nut member being elongated and having a length at least substantially twice its internal diameter, a downwardly facing beveled gear element connected with said nut member between the middle and an upper end of the nut member and substantially below the upper end of the nut member, a carrier supported by said nut member and having a first portion solely on top of said nut member and slidably embracing said screw rod, a pinion rotatably mounted on a second portion of said carrier and meshing with said gear element, said carrier including an arm extending between said first carrier portion and said second carrier portion and providing the sole means positioning said second carrier portion for supporting said pinion beneath the downwardly facing beveled gear element, means for rotating said pinion, and load supporting means on said carrier.
2. A lifting jack, as defined in claim 1, comprising an annular thrust bearing washer disposed between said nut member and said first carrier portion.
3. A lifting jack, as defined in claim 1, wherein said load supporting means includes a projection integral with and extending forwardly of said first carrier portion.
4. A lifting jack, as defined in claim 3, wherein said load supporting means includes a load engageable member pivotally supported on said projection.
5. A lifting jack, as defined in claim 4, wherein said load engageable member comprises pivot pin means, said projection including an upwardly facing and slightly upwardly inclined surface engaging beneath and supporting said pivot pin means, said pivot pin means being disengageable from said surface in the event of forward tipping of the jack while lifting a load.
6. A lifting jack, as defined in claim 1, wherein said means for rotating said pinion comprises a handle member including an elongated shank portion, said pinion including a shaft having a transverse aperture therethrough, said shank portion slidably extending through said aperture for enabling radial adjustment of said handle member.
7. A lifting jack, as defined in claim 6, wherein said handle member includes laterally projecting hand grip means at an outer end thereof, and means substantially at an opposite end thereof interengageable with said pinion shaft for preventing rotation of the handle about the axis of said handle shank portion.
8. A lifting jack comprising a generally vertically supported screw rod, a combined nut and gear member including an elongated internally threaded tubular portion having a length at least substantially twice its internal diameter threadedly mounted on said screw rod and a downwardly facing gear portion integrally connected with said tubular portion at least partially between the middle of the upper end of the tubular portion and substantially spaced below the upper end of the tubular portion, a carrier member including a first tubular portion slidably disposed on said screw rod above and supported by and solely on top of said nut and gear member, a bearing washer disposed between an upper end of said tubular portion of the nut and gear member and a lower end of said carrier member tubular portion, said washer including a peripheral depending flange overlapping the upper end of said nut and gear member tubular portion for resisting entry of dirt or foreign material between the washer and said upper end of the nut and gear member tubular portion, said carrier member including a single arm portion projecting rearwardly from said first portion and a tubular bearing portion supported at an outer end of said arm portion, a pinion rotatably mounted in said tubular bear-

ing portion and meshing with said gear portion, said carrier member including a load supporting projection integral with said first tubular portion thereof and projecting therefrom, and handle means connected with said pinion for rotating the pinion.

9. A lifting jack, as defined in claim 8, wherein said upper end of said nut and gear member tubular portion includes recess means therein for accommodating any foreign material which may enter between said upper end and the washer.
